E. BRUNHOFF

DISPLAY AND VENDING APPARATUS

Filed Aug. 8, 1923

Inventor
Edward Brunhoff
By C. W. Miles,
Attorney

UNITED STATES PATENT OFFICE.

EDWARD BRUNHOFF, OF CINCINNATI, OHIO, ASSIGNOR TO THE BRUNHOFF MANUFACTURING COMPANY, OF CINCINNATI, OHIO, A CORPORATION OF OHIO.

DISPLAY AND VENDING APPARATUS.

Application filed August 8, 1923. Serial No. 656,425.

To all whom it may concern:

Be it known that I, EDWARD BRUNHOFF, a citizen of the United States, residing at Cincinnati, in the county of Hamilton and 5 State of Ohio, have invented certain new and useful Improvements in Display and Vending Apparatus, of which the following is a specification.

My invention relates to improvements in 10 display and vending apparatus. One of its objects is to provide an improved lid with a transparent panel adapted to be applied to original containers, as for instance cigar boxes, to display the goods, to protect the 15 goods from dust and dirt, and to prevent undue escape of moisture from the goods while on display. Another object is to provide improved means to detachably attach a transparent lid to an original package to 20 provide a relatively tight joint, and to enable the transparent lid to be readily removed from one original package to another as soon as the goods have been vended therefrom. Another object is to provide an 25 improved detachable lid apparatus adapted to be attached to sheet metal original packages. Another object is to provide improved means to hinge the transparent lid and support it from the original package, 30 and to limit its range of movement so as to prevent liability of the weight of the transparent lid upsetting or overturning the original container due to movements of the transparent lid changing the disposition 35 of the weight and center of gravity. My invention also comprises certain details of form, and combination and arrangement of components, all of which will be fully set forth in the description of the accompanying drawings, in which;

Fig. 1 is a perspective view of an original container of sheet metal type with my improved transparent and detachable lid applied thereto.

Fig. 2 is a sectional detail showing the transparent lid at the limit of its raised position.

Fig. 3 is a perspective view of the transparent lid detached, and before it is hinged to its supporting member.

Fig. 4 is a sectional detail similar to Fig. 2, with the transparent lid in closed position.

Fig. 5 is a perspective view of substan-

tially one half of the transparent lid detachable supporting member.

The accompanying drawings illustrate the preferred embodiment of my invention in which 15 represents an original container or package, as for instance a sheet metal cigar box provided with a lid of sheet metal attached thereto by means of a series of hinge eyes formed integral with the box or container, a series of hinge eyes 17 formed integral with the lid 18, and a hinge axle 19.

The detachable lid comprises a panel 20 of glass or other transparent material of substantially the size to cover the open mouth of the container 15. A frame 21 of sheet metal is formed about the panel 20, preferably from a channel shaped strip of sheet metal, which is mitered at the corners and bent at the corners and fitted to the edges of the panel 20, with the ends 70 of said strip soldered together where they meet at one corner of the panel 20. A light narrow sheet metal frame is thus permanently attached to the panel 20. Along one edge of the sheet metal frame 21 are 75 soldered or otherwise attached short sections of sheet metal tubing 22 to form hinge eyes. A supporting member, to which the panel 20 and frame 21 are to be hinged, is formed by connecting a pair of angle 80 plates 24 and 25 together by means of a channel shaped cross-bar 28, to which said angle plates are soldered or otherwise rigidly attached.

Said angle plates 24 and 25 are designed 90 to engage opposite corners of the container 15 adjacent to the hinge attaching the lid 18 to the container 15. Each of said angle plates has a section 30 to engage the rear outer face of the container 15, and to pass 95 between the rear wall of the container 15 and the hinge eye 17 at the extreme end of the hinge axle 19. Each of said angle plates is provided with a face 31, provided 100 by folding the metal of the angle plates upon themselves, which faces 31 engage the exterior of the box at the sides thereof. Extending inwardly from the sides 31 of the angle plates are tongues 32 which hook 105 over the upper edge of the sides of the box, and embrace the side of the box between said tongue 32 and the face 31. The angle plates 24 and 25 and the cross bar 28 are

thus firmly but detachably mounted upon the upper edge of the box in front of the open box lid 18. The angle plates 24 and 25 and cross bar 28 may be made to fit boxes of different dimensions by changing the length of the cross-bar 28. A plurality of sheet metal tube sections 34 are rigidly attached to the cross-bar 28 to constitute hinge eyes by means of which and a hinge 10 axle 36 the transparent lid 20 is pivotally attached to the cross-bar 28 of the supporting member. The cross-bar 28 serves to limit the pivotal movement of the transparent lid 20 from a substantially horizontal closed position to a substantially vertical open position, and thereby prevents the center of gravity of the lid 20 being shifted far enough rearwardly to cause the box to be upset or overturned thereby.

20 The narrow sheet metal frame 21 and manner of hinging the same to the cross-bar 28 enables the panel 20 to be made large enough to display substantially all of the goods within the box, and enables 25 transparent lids of different sizes to be conveniently and economically produced without requiring separate sets of dies for the various sizes. The entire attachment to the original package is compact, strong, of 30 pleasing appearance, firmly mounted relative to the original package, and conveniently produced in a variety of sizes without the use of a large number of dies.

The apparatus herein shown and described is capable of considerable modification without departing from the spirit of my invention.

What I claim is:

1. In combination with a container having a lid permanently hinged thereto, a transparent lid to be detachably applied to said container for display purposes while the permanent lid is in its open position, a supporting member for said transparent lid comprising a cross-bar extending across in front of the permanent lid, angle plates at opposite ends of said cross-bar each having a plate to exteriorly embrace a side of the container and a plate to exteriorly embrace the rear of the container, said side engaging plates being provided with members extending over the top edge of the sides of said container to also engage the inner face of the sides of said container and means to hinge said transparent lid to the front of said cross-bar.

2. In combination with a container having a lid permanently hinged thereto at the up-

per rear edge of said container, a transparent lid to be detachably applied to said container for display purposes while the permanent lid is in its open position, a supporting member for said transparent lid comprising a cross-bar extending across the top of the rear wall of said container in front of the hinge of said permanent lid, angle plates rigidly attached to opposite ends of said cross bar and extending downwardly therefrom one to embrace exteriorly and interiorly the side walls of the container and the other to enter between the rear wall of said container and a hinge eye of said permanent lid, and means to hinge the transparent lid to the front of said cross-bar.

3. In combination with a container having a lid permanently hinged thereto at the upper rear edge of said container, a transparent lid to be detachably applied to said container for display purposes while the permanent lid is in its open position, a supporting member for said transparent lid comprising a cross-bar extending across the top of the rear wall of said container in front of the hinge of said permanent lid, angle plates rigidly attached to opposite ends of said cross bar and extending downwardly therefrom one to embrace exteriorly and interiorly the side walls of the container and the other to enter between the rear wall of said container and a hinge eye of said permanent lid, and means to hinge the transparent lid to the lower front edge of said cross-bar to enable the upper edge of said cross bar to serve as a stop and support for said transparent lid in the open position and to prevent upsetting the container.

4. In combination with a container having a lid permanently hinged thereto at the upper rear edge of said container, a transparent lid to be detachably applied to said container for display purposes while the permanent lid is in its open position, a cross-bar of channel shaped cross-section extending across in front of the permanent lid, angle plates at opposite ends of said cross-bar entering between the channel arms of said cross-bar and rigidly united to said cross bar and detachably engaging rear and side walls of the container at the upper and opposite rear corners of said container, and a metal bound transparent lid hinged to the lower front edge of said cross-bar.

In testimony whereof I have hereunto affixed my signature.

EDWARD BRUNHOFF.
